[57] CLAIM

The ornamental design for an automatic telephone apparatus, as shown and described.

DESCRIPTION

FIG. 1 is a front, top and left side perspective view of an automobile telephone apparatus showing my new design;

FIG. 2 is a top plan view thereof;

FIG. 3 is a front elevational view thereof;

FIG. 4 is a left side elevational view, the right side being substantially a mirror image thereof; and

FIG. 5 is a rear elevational view thereof.

Fig. 1.

Fig. 2.

Fig.3.

Fig.4.
